UNITED STATES PATENT OFFICE.

CHARLES C. CHERRY, OF HIDALGO, ILLINOIS.

POST.

1,156,207.

Specification of Letters Patent.

Patented Oct. 12, 1915.

Application filed April 20, 1915. Serial No. 22,672.

To all whom it may concern:

Be it known that I, CHARLES C. CHERRY, a citizen of the United States, residing at Hidalgo, in the county of Jasper and State of Illinois, have invented new and useful Improvements in Posts, of which the following is a specification.

This invention relates to posts and more particularly to clothes line posts.

10 One of the principal objects of the invention is to provide a post having novel means for simultaneously elevating the lines and placing them under proper tension to sustain the clothes carried thereby.

15 Another object of the invention is the provision of simple and efficient means for properly bracing the post so as to prevent sagging of the lines and to hold the lines under constant tension so as to prevent 20 clothes from dragging on the ground and becoming soiled.

25 Another object of the invention is the provision of a fence post having means for supporting two widely separated lines and for simultaneously raising said lines and placing each line under tension independently of the other line.

30 Further objects of the invention will appear as the following description is read in connection with the accompanying drawing, which forms a part of this application, and in which:—

Figure 1 is a front elevation. Fig. 2 is a side elevation. Fig. 3 is a rear elevation. 35 Fig. 4 is a top plan view. Fig. 5 is a detail vertical sectional view. Fig. 6 is a perspective view of the locking dog. Fig. 7 is a perspective view of one of the adjusting keys.

40 In the specific embodiment of the invention as illustrated herein, the post generally indicated at 1 is preferably constructed of a galvanized channel iron, the parts of which are identified as follows, 2 indicating the 45 body portion, and 3 and 4 the side flanges.

The post is cut vertically for a short distance from the bottom at each corner thus separating the body portion from the side flanges, as will be readily understood. The 50 body portion is bent rearwardly into a horizontal foot 5 while the side flanges are bent inwardly, as shown, and overlap each other. When the post is embedded in the ground the foot and the inwardly bent portions of 55 the side flanges will form retaining mem-

bers which will prevent lifting of the post, as will be readily understood.

The side flanges 3 and 4 are provided with a plurality of holes, through two of which are passed the pivoting bolts 6 and 7, the former having pivoted thereon a diagonally extending brace 8 while the latter has pivoted thereon a platform 9 having raised lugs 10 which are engaged by the free end of the brace. By forcing inwardly upon the free end of the brace the free end of the platform will be depressed upon the surface of the ground and the post properly braced against any forward movement of its upper end, as will be readily understood. Formed 70 in opposite side flanges and in the same plane are arcuate slots 11 forming very near a complete circle, as shown. Mounted in these slots is a substantially crescent shaped shaft 12 in the center of which is secured an operating lever 13 which passes through a vertical slot 14 formed in the body and which carries a locking dog 15 arranged to engage in the lateral notches 16 formed in the side walls of the slot 14 and limited in 80 its outward movement by means of the laterally extending arms 17, the dog being freely slidable upon the lever.

Mounted upon each end of the shaft which in practice extends about five feet upon each side of the post are line supporting springs 18 having their inner terminals hooked over one edge of the semi-circular shaft 12 and wound around said shaft in engagement therewith to the opposite edge. The next 90 coil of the spring is then separated from the shaft and its free end extended off at a tangent with the terminal thereof formed into a line engaging hook 19. Each of the springs is held in position against longitudinal movement on the shaft by means of the keys 20 which as shown in Fig. 7 are constructed each of a single piece of wire bent back upon itself to form the separated legs which straddle the coils of the spring and 95 pass through openings 21 formed adjacent opposite edges of the shaft 12. These keys are held in adjusted position radially of the shaft by means of cotter pins 22 which pass through openings formed in one leg 105 of the key as shown in Fig. 7, and may be removed so as to place them upon either side of the lower wall of the shaft. The yoke portion of each key is bent inwardly to produce a bifurcation in which the free 110

end of its associated spring is seated. By adjusting either key in the shaft the distance of the hook 19 from the shaft may be properly regulated.

5 When the lever 13 is raised to the upper end of the slot 14 the hooks 19 will be in lowermost position and also in their farthest forward position. When the lever is depressed and the dog engaged in one pair 10 of the notches 16 the hooks 19 will be elevated and the lines placed under tension. In this manner it will be seen that clothes may be hung upon the lines when they are lowered and the lever then operated to elevate the lines and place them under tension 15 so that the clothes will be properly supported above and prevented from dragging on the ground.

What is claimed is:—

20 1. A support for clothes lines comprising a post, a shaft journaled in the post, means for rotating the shaft, means for holding the shaft in adjusted position, and resilient means for connecting a line to the post 25 which when the shaft is rotated will elevate the line and place the same under tension.

2. A support for clothes lines comprising a post, a shaft journaled in the post, means for rotating the shaft, means for holding 30 the shaft in adjusted position, resilient means for connecting a line to the post which when the shaft is rotated will elevate the line and place the same under tension, and means for regulating the height and 35 tension on the lines.

3. A clothes line supporting device com-

prising a post, a shaft journaled in the post, means for rotating the shaft, means for holding the same in adjusted position, means mounted upon the ends of the shaft for connecting a pair of lines to the shaft, means for retaining said connecting means in position on the shaft, and means for adjusting the retaining means, said connecting means adapted to raise the lines and place tension 40 thereon when the shaft is rotated and said retaining means adapted to independently control the height and tension of each line.

4. A clothes line supporting device comprising a post, resilient means for connecting a line to the post, means for placing tension on the line and an adjustable brace carried by the post and adapted to hold the post in upright position against the tension 50 of the line.

5. A clothes line supporting device comprising a post, a shaft journaled in the post, spiral springs connected to opposite ends of the shaft and having tangential ends 60 provided with line engaging hooks, retaining keys passing through the shaft and straddling certain coils of the spring, said retaining members having bifurcated ends for supporting the tangential ends of the spring, and means for rotating the shaft and 65 holding the same in adjusted position.

In testimony whereof I affix my signature in presence of two witnesses.

CHARLES C. CHERRY.
